MIRROR VIEWING DEVICE

Robert B. J. Diggins, Kansas City, Mo.

Application February 4, 1955, Serial No. 34,362

Term of patent 7 years

(Cl. D57—1)

Fig. 1.

Fig. 2.

Fig. 1 is a perspective view of the mirror viewing device, showing my new design; and

Fig. 2 is an end elevational view thereof.

I claim:

The ornamental design for a mirror viewing device, as shown.
